(57) **CLAIM**

The ornamental design for an ultrasound scanner support, as shown and described.

DESCRIPTION

FIG. 1 is a top, left isometric view of an ultrasound scanner support showing my design.

FIG. 2 is a front elevational view thereof.

FIG. 3 is a rear elevational view thereof.

FIG. 4 is a right-side elevational view thereof with the left-side view being a mirror image of FIG. 4.

FIG. 5 is a top plan view thereof; and,

FIG. 6 is a bottom plan view thereof.

The broken lines are included for the purpose of illustrating portions of the ultrasound scanner support that form no part of the claimed design.
